[57] CLAIM

The ornamental design for a tire, as shown and described.

DESCRIPTION

FIG. 1 is a perspective view of a tire showing one embodiment of my new design, it being understood that the tread pattern is substantially the same throughout the circumference of the tire, as shown schematically by solid lines, the opposite side being substantially the same as that illustrated;

FIG. 2 is an enlarged, fragmentary plan view of the embodiment of FIG. 1;

FIG. 3 is a perspective view of a tire showing another embodiment of my new design, it being understood that the tread pattern is substantially the same throughout the circumference of the tire, as shown schematically by solid lines, the opposite side being substantially the same as that illustrated; and,

FIG. 4 is an enlarged, fragmentary plan view of the embodiment of FIG. 3.

FIG. 1

FIG. 2

FIG. 3

FIG. 4
